UNITED STATES PATENT OFFICE

2,446,357

TURN SHOE AND METHOD OF
MANUFACTURE

Anthony Vigorith, Cincinnati, Ohio

Application October 17, 1945, Serial No. 622,875

9 Claims. (Cl. 36—19)

1

This invention relates to improvements in a turn shoe, and a method of manufacturing same.

An object of the invention is to facilitate and expedite the manufacture of turn shoes, with a substantial saving of time, labor, and materials.

Another object is to dispense with the use of complicated and expensive machinery to a substantial extent in the manufacture of turn shoes, and to so simplify the operations that superior shoes may be produced by workers having limited experience in the trade.

Another object is to produce a shoe which is more flexible and comfortable than the ordinary turn shoe, and which will possess desirable wearing qualities heretofore unattained in the production of turn shoes.

Another object is to produce a turn shoe which will hold its shape longer than turn shoes customarily do, and which will better withstand the operation of re-soling by a repairman.

Another object of the invention is to produce a turn shoe which is built upon an insole, thereby eliminating the usual heavy outsole required for providing the customary channel in which the upper is usually fixed.

Another object is to make unnecessary the use of costly high grade materials in a turn shoe, as was formerly required.

The foregoing and other objects are attained by the means described herein and illustrated in the accompanying drawings, in which:

Fig. 1 is a perspective view of a shoe upper with a lining therein, cut and shaped for use in performing the method of the invention, the insole being not yet applied.

Fig. 2 is a perspective view of an insole such as is applicable to the upper of Fig. 1.

Fig. 3 is a side elevational view of the shoe with the insole attached along the major portion of its length, the toe of the upper being unattached, and the upper being turned with its lining to the outside.

Fig. 4 is an enlarged cross-sectional view taken on line 4—4 of Fig. 3, and showing the shoe turned inside out.

Fig. 5 is a view similar to Fig. 3, showing the shoe in turned condition, that is, with the upper lining to the inside.

Fig. 6 is a perspective view of a metal reinforced shank piece to be inserted in the shoe as illustrated by Fig. 5.

Fig. 7 is an enlarged cross-sectional view taken on line 7—7 of Fig. 5.

Fig. 8 is a bottom view of the shoe with the shank piece inserted and the toe and heel portions lasted in, the character 34 indicating a portion of the outsole.

As is well known in the shoe industry, the turn shoe has been widely accepted as one of the most comfortable and flexible shoes available. However, turn shoes have always been expensive

2

because of the complexity of the operations necessary to the turn shoe process of manufacture, and for the further reason that highly skilled labor and the best of materials had to be employed. Although the use of high grade materials and workmanship resulted in the production of a fine shoe, certain disadvantages resulted from the manner in which the shoe was manufactured. For example, the ordinary turn shoe required the use of not less than a ten iron sole, but after the channel was cut into the sole to approximately half its thickness, about half of the wear of the sole was destroyed. In other words, when the sole wore through to the base of the channel, the shoe then began to spread out and fall apart, since nothing remained for holding the shoe together. Shoes thusly worn through to the base of the channel usually were found to be in such condition as to render impossible the re-soling or repair thereof.

All of the foregoing disadvantages have been eliminated by means of the present invention. In accordance with the invention, the turn shoe is provided with a flexible insole which readily

permits turning, and neither the insole nor the outsole requires channeling in cementing the upper assembly to the outsole. Consequently, a much thinner outsole can be applied to the turn shoe made in accordance with the present invention, and since turning of the shoe is accom-

plished with less effort and destructive effect than heretofore, it is possible to employ common and less expensive materials in the manufacture of the shoe, in place of the costly high grade materials formerly required. Moreover, the major part of the work of constructing the present shoe can be performed in the fitting department, with the elimination of such equipment as the assembly machine, the pulling over

machine, and the side lasting staple machine. The entire shoe can be reproduced using only an ordinary sewing machine, a bed toe lasting machine, and a seat lasting machine, it being possible of course to eliminate the last two machines in the production of toeless shoes having no counters in the heels.

Referring to Fig. 1 of the accompanying drawings, 12 indicates the shoe upper and 13 indicates the cloth upper lining within it. The member 14 which forms the counter pocket is indicated at 14. In accordance with regular practice, the upper 12 which is shown inside the shoe Fig. 4, may be made in two halves stitched together as at 15, it being customary for the seam to extend

from toe to heel. The lining likewise may be formed of two or more pieces stitched together as at 16. Member 14, also of two pieces, may be stitched together at 17, and sewed along the edges at 18 for securing it to the upper lining.

These parts are shown in the proper relationship upon Fig. 1 of the drawings, whereas in Fig. 3

they are shown as they appear when the upper is turned inside out.

The open top of the shoe, indicated at 17, may be given any desired contour to satisfy the demands of style, and will ordinarily be hemmed or beaded as shown. The lower edges of the upper will preferably be cut away at both sides of the shoe between the toe portion 19-19 and the heel portion 20-20, to conserve material and to provide for narrow flanges between those points, at which flanges the upper is stitched to the insole 23 as illustrated by Fig. 4, wherein the flanges are indicated at 21-21, and the stitching at 22-22.

The insole 23, as illustrated by Fig. 2, has a toe end 24 and a shank end 25, the latter being fore-shortened so as to reach approximately to the breast of the shoe heel when attached. This insole may be of any flexible material, not necessarily costly, such as split leather, composition, pig leather, or the like, and may be as light as 1½ to 2 iron material, as compared with the customary 3½ iron sole leather generally employed in any shoe manufacture for anchoring the edges of the shoe upper. The insole 23 is not channeled or skived in any manner whatsoever. For establishing a uniform margin along which the lower edges of the upper may be stitched, as at 22, the insole may be marked with pencil or other lines 26-26, which do not penetrate the surface of the insole. Before the upper is stitched to the insole, it is first turned inside out, as illustrated by Figs. 3 and 4, the stitching 22 being applied while the upper is in this condition. The shoe then presents the appearance of Fig. 3.

The next operation is that of turning the shoe of Fig. 3, to dispose the lining 13 to the inside and expose the upper material 12. This turning of the shoe produces the results indicated by Fig. 5, wherein the upper lining is inside the shoe and the insole 23 is attached, with the stitchings inside the shoe (Fig. 7). It will here be noted that the toe and heel portions of the upper remain free of attachment to the insole.

As the next operation, a heel counter will be inserted in the back of the shoe, as by means of a counter pocket generally employed for this purpose, and then the shank piece 27 of Fig. 6 will be placed inside the shoe with its heel end 28 abutting the back of the shoe. This places the shoe in condition for inserting the last, and lasting the heel and toe.

In lasting the heel and toe, common practice is resorted to, which usually consists in turning in the toe and heel margins or flanges 19-19 and 20-20, as shown in Fig. 8, and fastening them by means of tacks or adhesive, or both. By way of example, the toe material at 19-19 is lasted and secured to the outer surface of the insole by means of an adhesive, whereas at the heel, the material 20-20 is securely tacked to the shank piece 27, the tacks being shown at 30. Incidentally, the shank piece of fiber or other comparatively stiff material, may be reinforced and maintained in shape by means of a formed metallic strip or member 31 applied thereto before insertion of the shank piece into the shoe. Usually the reinforcing member is of rigid steel construction, and is tacked to the shank piece at one or both of its ends, as at 32.

The shoe construction having been advanced to the stage illustrated by Fig. 8, will be found free of wrinkles and bulges in the material of the upper, with a neat close fitting form, this result being readily attained as the upper is drafted

in snugly against the last with ease and rapidity, due to the extreme flexibility of the entire structure.

The shoe is now ready for pounding and roughening of the insole bottom, after which the heel and the outsole 34 may be attached in the usual manner, the latter by cementing it in place, or by lockstitching 35.

If desired, a filler may be interposed between the outsole and the insole, although this is not considered necessary in shoes constructed as herein disclosed.

As will be readily appreciated, the outsole of this shoe, as well as the insole, may be formed of light weight leather, composition, or the like, when a dainty stylish shoe is required; and in so lightening the shoe there will be no sacrificing of strength and wearing qualities as is the case when the sole is channeled and cut partially through toward the wearing surface of the sole. Moreover, a shoe constructed as herein disclosed may be worn until the outsole has practically disappeared, and yet the shoe will not spread and fall apart, but will remain in good condition for resoling.

So far as the manufacturing process is concerned, persons skilled in the art of shoe construction will readily appreciate the advantages of eliminating the complex machine operations performed by the assembly machine, the pulling-over machine, and the side lasting staple machine, with the result that the major portion of the work may be performed in the fitting department of the factory by using ordinary sewing machines. Obviously, the savings of time, labor, and materials of a costly nature, are substantial and highly advantageous to the manufacturer, who gains the added advantage of producing without the aid of highly skilled labor. Finally, the purchaser gains the advantage of wearing an extremely flexible and comfortable shoe at low cost, with a wide choice as to the weight of shoe desired. The shoe will of course present the same outside appearance as any single sole shoe.

What is claimed is:

1. The method of manufacturing a turn shoe, which method comprises the steps of assembling an upper and an upper lining, turning said assembly inside out, securing the side portions of the lower edges of the upper to a flat unchanneled insole, exclusive of the toe and heel portions of the upper, turning the connected upper and insole right side out with the lining inside the upper, then inserting a shank piece inside the upper, and thereafter preparing the shoe for application of an outside to the insole, by lasting-in the toe and heel portions of the upper.

2. The method of manufacturing a turn shoe, which method comprises the steps of assembling an upper and an upper lining, turning said assembly inside out, securing the side portions of the lower edges of the upper to a flat unchanneled insole, exclusive of the toe and heel portions of the upper, turning the connected upper and insole right side out with the lining inside the upper, then inserting a heel counter and a metal reinforced shank piece inside the upper, and thereafter preparing the shoe for application of an outsole to the insole, by lasting-in the toe and heel portions of the upper.

3. The method of manufacturing a turn shoe, which method comprises the steps of assembling an upper and an upper lining, turning said assembly inside out, securing the side portions of

the lower edges of the upper flatwise upon a flat insole which comprises a toe end and a heelless shank end, leaving the toe portion free of attachment to the toe end of the insole, turning right side out the connected upper and insole, with the lining inside the shoe, then inserting into the shoe a shank piece including a heel portion which reaches the back of the shoe upper, while the shank portion thereof overlies the shank portion of the insole, applying a last to the shoe and lasting-in the toe and heel portions of the upper onto the insole and the heel portion of the shank piece, respectively, and thereafter fixing an outsole in covering relationship to the insole and the lasted-in toe and heel portions of the upper, and applying a heel to the outsole.

4. The method of manufacturing a turn shoe, which method comprises the steps of assembling an upper and an upper lining, turning said assembly inside out, securing the side portions of the lower edges of the upper flatwise upon a flat insole which comprises a toe end and a heelless shank end, leaving the toe portion free of attachment to the toe end of the insole, turning right side out the connected upper and insole, with the lining inside the shoe, then inserting into the shoe a heel counter and a rigidly reinforced shank piece including a heel portion which reaches the back of the shoe upper, while the shank portion thereof overlies the shank portion of the insole, applying a last to the shoe and lasting-in the toe and heel portions of the upper onto the insole and the heel portion of the shank piece, respectively, and thereafter fixing an outsole in covering relationship to the insole and the lasted-in toe and heel portions of the upper, and applying a heel to the outsole.

5. The method of manufacturing a turn shoe, which method comprises the steps of assembling an upper and an upper lining, and with the assembly turned inside out securing the side portions of the lower edges of the upper to the side marginal portions of a flat unchanneled insole, exclusive of the toe and heel portions of the upper, with the side edges of the insole extended outwardly beyond said lower edges of the upper as secured to the insole, then turning the connected upper and insole right side out with the lining inside the upper, thereby to dispose the insole wholly within the shoe, then inserting a shank piece inside the upper, and thereafter lasting-in the toe and heel portions of the upper to prepare the shoe for application of an outsole over the insole and the lower edges of the upper thereto secured.

6. The method of manufacturing a turn shoe, which method comprises the steps of assembling an upper and an upper lining, and with the assembly turned inside out securing the side portions of the lower edges of the upper to the side marginal portions of a flat unchanneled insole, exclusive of the toe and heel portions of the upper, with the side edges of the insole extended outwardly beyond said lower edges of the upper as secured to the insole, then turning the connected upper and insole right side out with the lining inside the upper, thereby to dispose the insole wholly within the shoe, then inserting a shank piece and a heel counter inside the upper, and thereafter lasting-in the toe and heel portions of the upper upon the insole and the heel counter, respectively, to prepare the shoe for application of an outsole over the insole, the lower edges of the upper thereto secured, and the lasted-in toe and heel portions.

7. The method of manufacturing a turn shoe, which method comprises the steps of assembling an upper and an upper lining, turning said assembly inside out, securing the side portions of the lower edges of the upper flatwise upon a flat insole which comprises a toe end and a heelless shank end, leaving the toe portion free of attachment to the toe end of the insole and permitting the side edges of the insole to extend outwardly beyond the lower edges of the upper, then turning right side out the connected upper and insole, with the lining inside the shoe, then inserting into the shoe a shank piece including a heel portion which reaches the back of the shoe upper, while the shank portion thereof overlies the shank portion of the insole, applying a last to the shoe and lasting-in the toe and heel portions of the upper onto the insole and the heel portion of the shank piece, respectively, and thereafter fixing an outsole in covering relationship to the insole and the lasted-in toe and heel portions of the upper, and applying a heel to the outsole.

8. A turn shoe structure comprising in combination, a plain and flat unmutilated insole having a toe portion, a shank portion, and a ball portion, a heel shank piece, a shoe upper with a lining therein, the upper including a heel portion with a depending flange lasted to the heel shank piece, a toe portion having a depending flange lasted to the toe portion of the insole, and an intermediate portion including lower edges located between the depending flanges of the toe and heel portions of the upper, an evaginated connection securing the intermediate portion of the upper to the insole marginally at the ball portion of the latter, with the lower edges of the upper set inwardly from the insole side edges, a plain flat unmutilated outsole overlying the insole, the lower edges of the shoe upper, and the lasted-in toe and heel flanges, and means concurrently securing the outsole to the upper and the insole.

9. A turn shoe structure comprising in combination, a plain and flat unmutilated insole having a toe portion, a shank portion, and a ball portion, a heel shank piece, a shoe upper with a lining therein, the upper including a heel portion with a depending flange lasted to the heel shank piece, a toe portion having a depending flange lasted to the toe portion of the insole, and an intermediate portion including lower edges located between the depending flanges of the toe and heel portions of the upper, an evaginated connection securing the intermediate portion of the upper to the insole marginally at the ball portion of the latter, a plain flat unmutilated outsole overlying the insole, the lower edges of the shoe upper, and the lasted-in toe and heel flanges, and means concurrently securing the outsole to the upper and the insole.
